INTERCHANGEABLE HEEL FOR SHOES

Filed Aug. 13, 1928

1760. 1.

ALBERT SHAHBENDER

BY *Victor G. Evans*

WITNESS:

G. Weston, Trusty.

ATTORNEY

UNITED STATES PATENT OFFICE.

ALBERT SHAHBENDER, OF ASTORIA, NEW YORK.

INTERCHANGEABLE HEEL FOR SHOES.

Application filed August 13, 1928. Serial No. 299,217.

This invention relates to new and useful improvements in interchangeable heels for shoes.

The primary object of my invention resides in a heel attaching means for shoes, which includes a male or attaching member which is permanently fixed to the heel portion of the first lift of a shoe to slidably receive a female member or detachable heel for interlocking engagement therewith which facilitates the changing of the heels from one shoe to the other after they become slightly worn down on one side or replaced by new heels when completely worn out.

Another object of the invention is to provide an interchangeable heel which is slidably attached to a shoe and a locking means for holding the same against accidental separation of the heel therefrom after the same has been locked in position upon the shoe.

Another object is to provide a removable heel which can be attached to any type of shoe and which will eliminate the difficulties experienced by the shoemaker in replacing heels on shoes in general and especially women's shoes.

A still further object of my invention resides in an interchangeable heel that can be applied or removed from a shoe by one unskilled in the art of shoe repair.

With these and other objects in view, the invention resides in certain novel construction and combination and arrangement of parts, the essential features of which are hereinafter fully described, are particularly pointed out in appended claims and are illustrated in the accompanying drawing, in which—

Figure 1 is a fragmentary side elevation of a shoe showing my improved interchangeable heel in section attached and locked thereto.

Figure 2 is a vertical transverse sectional view taken on line 2—2 of Fig. 1.

Figure 3 is a similar view taken on line 3—3 of Fig. 1.

Figure 4 is a detail perspective view of the attaching member and heel portion in separated position.

Figure 5 is an enlarged longitudinal sectional view taken on the line 5—5 of Fig. 4.

Figure 6 is a vertical transverse sectional view through a rubber heel showing a metal plate embedded therein for slidably receiving the attaching member shown in Fig. 4.

Referring more particularly to the draw-

ing by reference characters, the numeral 10 designates my improved interchangeable heel in its entirety, which includes a male attaching member 11 and a female member or detachable heel 12.

The male or attaching member 11 includes a stamped metal plate 13 having its side and rear edges bent upwardly, outwardly and downwardly to provide a resilient flange 14, the front end being open. Mounted at the front open end, is a locking device 15 which comprises a clamping tongue 16 mounted for swinging movement on a pivot pin 17 journalled in opposed side walls of an opening 18 provided in the plate, as shown in Fig. 5 of the drawing. The gripping edge of the tongue has teeth 20 provided thereon while the opposite end is provided with a loop or eye 21 to receive the hook 22 of an actuating lever 23 which is slidably mounted in a guide 24 mounted adjacent the front edge of the body as clearly shown in Fig. 4 of the drawing, while the opposite end of the lever is bent downward to provide a manipulating finger 25 by which the same may be moved to a locked or unlocked position. Shoulders 26 provided on the lever 23 strike the sides of the loop 21 when the lever is pushed in which turns the same into a locked position as shown in dotted lines of Fig. 5. To hold the lever in locked position I provide a seat 27 pressed from the lever, which coacts with a notch 28 provided in the plate adjacent the front edge thereof. Suitable spaced openings 29 are provided in the plate for the passage of fastening nails 30 to hold the attaching members permanently to the underside of the heel portion 31 of the first lift 32 of a shoe 33.

The female or detachable heel 12 comprises a solid body 34 provided with a recess 35 in the top thereof, of a shape similar to that of the plate 13 and which opens at the front end thereof.

A groove 36 is formed in the inner walls of the recess to provide a wedge shaped flange 37 along the sides and rear edges thereof. A notch 38 is provided in the bottom wall of the recess centrally thereof inward of the front edge, to facilitate the locking of the heel in place by the locking tongue which will be presently explained.

In practice the attaching member 11 is permanently fixed to the shoe with the open end of the body towards the toe as clearly shown in Fig. 1 of the drawing. The tongue 16 of the locking device is swung to a hori-

zontal position as shown in full lines as in Fig. 4 and the open end of the recess 35 in the heel member 12 is placed at the rear end of the attaching member and as the flange 14 slides within the groove 36, the wedge shaped flange 37 will draw the heel tight against the lift of the shoe and hold the edges of the heel snug thereagainst.

After the heel has been set in place, the lever 23 is pushed in or towards the rear of the shoe and as the shoulders 26 strike the tongue 21, the toothed end of the arm swings down into the notch 38 to grip therein and hold the heel locked as the seat 27 becomes seated in the notch 28 in the attaching member which prevents the same from accidentally becoming unlocked.

When it becomes necessary to change the heels either from the right shoe to the left shoe and vice versa or to place new heels thereon, the wearer of a shoe need not take the shoes to a repair shop as a sharp instrument, such as a screw driver or the like can be forced between the front of the heel member and the depending finger 25 of the lever 23 to pry the same into an open or extended position. As the hook 22 comes in contact with the loop 21 the tongue will swing to a horizontal position as shown in full lines of Fig. 5 of the drawing which will permit the old heel to be taken off and new ones replaced and the parts swung back into place the same as described above, to lock them.

Although I have shown a man's shoe it will be appreciated that my invention will be advantageous in the changing and replacing of heels on women's shoes as it is very difficult to put heels on this type of shoe.

In Fig. 6 I have shown a rubber heel 12 comprising a rubber body 50 having a metal plate 51 embedded therein which is bent to the shape of the recess 35 in the heel of the preferred form and is provided with an opening 52, below which is a pocket 53 in the rubber to receive the tongue 16 of the locking device when in locked position upon a shoe.

What I claim as new is:

1. An interchangeable heel including an attaching plate adapted to be fixedly mounted to a shoe, a heel section slidably mounted on said plate having a notch therein, a locking tongue pivotally mounted on said plate for movement into locking engagement with said notch and for unlocked position therefrom, and an actuating member slidably mounted on said plate and operatively connected to said tongue for manually imparting locking and unlocking movements to the latter.

2. An interchangeable heel including an attaching plate adapted to be fixedly mounted to a shoe, a heel section slidably mounted on said plate having a notch therein, a locking tongue pivotally mounted on said plate for movement into locking engagement with said notch and for unlocked position therefrom,

and an actuating member slidably mounted on said plate and operatively connected to said tongue for manually imparting locking and unlocking movements to the latter, and coacting means between said actuating member and said plate for holding the said actuating member against movement when said tongue has been moved thereby to a locked position.

3. An interchangeable heel for shoes including an attaching plate adapted to be fixedly mounted to a shoe and provided with side flanges and a rear end flange, a heel section provided with a recess in the top face thereof of a shape corresponding to the shape of said plate, channels provided in the walls of said recess to receive said flange upon sliding of the heel section onto said plate, a notch provided in the bottom wall of said recess, a locking tongue pivoted to said plate, and an actuating member slidably mounted on said plate and extending beyond the front end thereof and operatively connected to said locking tongue to swing the same to horizontal unlocked position and vertical locked position into said notch upon the respective outward and inward sliding of said actuating member.

4. An interchangeable heel including an attaching plate adapted to be permanently fixed to the heel portion of a shoe having its side and rear edges bent upwardly, outwardly and downwardly to provide a continuous flange, a detachable heel section of a shape corresponding to the shape of said plate having a recess in the top face thereof, a groove provided in the side walls of said recess for slidably receiving said flange when attaching the heel section to said plate, a notch provided in the bottom wall of said recess, a locking tongue pivoted to said plate for locking engagement with said notch, and an actuating member slidably mounted on said plate and operatively connected to said locking tongue and having a manipulating portion extending beyond the front end thereof to swing the same to a vertical locked position into said notch, and to a horizontal unlocked position upon the respective inward and outward sliding of said actuating member.

5. A heel of the class described including an attaching plate, adapted to be permanently fixed to the heel portion of the first lift of a shoe, having its side and rear edges bent upwardly, outwardly and downwardly at a slight angle to provide a flange on said edges, a detachable heel section having a recess in the top face thereof of a shape corresponding to the shape of said plate to receive said plate, a notch provided in the bottom wall of said recess, a locking tongue pivoted to said plate in an aperture which registers with said notch when said heel section is in position on said plate, an actuat-

ing member slidably mounted on said plate and extending beyond the front edge thereof and provided with a depending finger, a hook provided on the inner end of said actuating member for swinging said locking tongue to a horizontal unlocked position, shoulders provided on said actuating member to swing said tongue to a vertical locked position upon the respective outward and inward sliding of said actuating member, and means for holding said actuating member against accidental movement when in locked position.

In testimony whereof I have affixed my signature.

ALBERT SHAHBENDER.
